UNITED STATES PATENT OFFICE.

LOUIS A. HOERR, OF ST. LOUIS, MISSOURI.

SEAL-LOCK.

SPECIFICATION forming part of Letters Patent No. 645,096, dated March 13, 1900.

Application filed April 7, 1899. Serial No. 712,185. (No model.)

To all whom it may concern:

Be it known that I, LOUIS A. HOERR, a citizen of the United States, residing at St. Louis, in the State of Missouri, have invented a new and useful Improvement in Seal-Locks and Analogous Devices, of which the following is a specification.

My invention relates chiefly, but not entirely, to seal-locks for cars; and the chief object of my improvements is to provide a seal-lock which will combine strength, efficiency, and durability with great simplicity and cheapness. I achieve that object by mechanism of which two forms are illustrated in the accompanying drawings, in which—

Figure 1 is a front elevation of a preferred form of seal-lock embodying my improvements. Fig. 2 is a plan view. Fig. 3 is a front elevation of a detail. Fig. 4 is a detailed isometric projection of the front of the preferred form of hasp. Fig. 5 is a detailed rear end view of the hasp. Fig. 6 is an enlarged detailed view of the back of the preferred form of hasp-head. Fig. 7 is a front end elevation of a modification of my device. Fig. 8 is a plan view of the same, and Fig. 9 is a detailed view of the form of keeper illustrated in Figs. 7 and 8.

Similar letters refer to similar parts throughout the several views.

A represents a car-door, B a door-post, and B' a batten, all of ordinary construction.

C represents a staple of common form.

D represents my improved hasp, which is shown pivoted at d upon the staple C.

In the preferred form of my hasp D' represents the base; d', strengthening ribs or webs; D², an inwardly-turned head whose face d² is preferably made concave, as shown, so as to prevent its not fitting its keeper by reason of roughness incident to casting, and which is preferably provided with a backwardly-extending wing d³ and a forwardly-extending wing d⁴. The outer edge d⁵ of the former is curved inwardly, and the outer edge d⁶ of the latter is curved outwardly, substantially in the arcs of the circles in which they respectively swing, and the rear side d⁷ and the front side d⁸ of the hasp-head are preferably curved in arcs of circles substantially parallel with the curves of the outer edges of said wings, as illustrated by Figs. 1, 4, and 6.

The modified form of the hasp D illustrated in Figs. 7 to 9, inclusive, differs from the preferred form in not having ribs d' or the forwardly-extending wing d⁴, which wing, though it adds strength to my device, is not essential to its operation, and when said wing is omitted the curvature of the front side d⁸ of the head is ordinarily immaterial and may be omitted. 55

D⁹ represents an arm extending down from the outer end of the hasp, which in the most complete form of my device, Figs. 1 to 6, is provided with a seal-wire opening d¹⁰ and a loop d¹¹, having a padlock-hole d¹²; but inasmuch 65 as padlocks are not generally used the loop d¹¹ may usually be dispensed with, as in the more simple form illustrated in Figs. 7 to 9.

E represents a keeper preferably having a base e, which may be secured to the door-batten B' by screws e' or other suitable means. It is preferably provided with forwardly-projecting parts E' and E², with a space or slot E³ between them, as shown in Figs. 1 to 6, inclusive; but where the hasp-head is formed with only one wing d³, as shown in Figs. 7 to 9, inclusive, the part E² is preferably omitted from the keeper. The part E' projects forward, so as to form beneath its front edge or lip a curved recess or 70 socket e² for the wing d³ of the hasp-head, and its bottom is preferably curved, as indicated by dotted lines in Figs. 1 and 3, so as to conform substantially to the preferred curvature of the rear end edge of the wing d³, which 75 said socket is designed to receive. The outer edge or lip e⁴ of the part E' is also preferably curved outward in the arc of a circle substantially parallel with the circle in whose 80 are the outer side of the hasp-head swings 85 and is preferably adapted to fit against that side of said head snugly when the seat is locked, whether in its lowest or highest position. The edge of the lip e⁵ of the part E² is preferably curved inward in a vertical plane 90 and is preferably substantially parallel with the outwardly-curved lip e⁴ of the part E, and in the preferred form of my device it extends forward, so as to form an inwardly-curved 95 socket e⁶ beneath it for the reception of the front end of the wing d⁴ of the preferred form 100 of my hasp-head.

E⁴ represents a stop shown projecting forward from the face of the part E'. When the

hasp-head is in its lowest position in the keeper, the bottom of the hasp preferably rests on this stop. It is preferably provided with a seal-wire opening e^7 , which is preferably 5 oblong in shape.

In the preferred form of my device the keeper E is also provided with a forwardly-projecting part E⁴, opposite the part E⁴, which is provided with a seal-wire opening e^8 , but 10 this part, though convenient, may be dispensed with without greatly affecting the value of my device. It is shown omitted in the form illustrated in Figs. 7 to 9.

Where the hasp is provided with the loop 15 d^8 , the keeper is provided with a corresponding loop E⁶, designed to coöperate with it and having a padlock-hole e^9 . Under other circumstances said loop E⁶ may be omitted, as in the form illustrated in Figs. 7 to 9, inclusive.

20 It sometimes happens that car-doors either get slightly warped or cannot be completely closed for some other reason, and under such circumstances and when the hasp-head cannot be forced down as low as the position in 25 which it is shown the preferred oblong form of the seal-wire openings prevents there being any difficulty in inserting the seal-wire. Where no padlock is used, the seal-wire may in the form shown in Figs. 1 to 6 be passed 30 through the padlock-holes hereinbefore described. So, also, the seal-wire may be passed through the padlock-hole d^9 and the seal-wire hole e^7 in case of necessity. On account of the curved form of the slot e^2 and the hasp-

head the latter fits the slot in the keeper-head 35 snugly in all positions, and when the hasp-head is seated in its slot the usual strains upon the hasp have no tendency to unseat it or break the seal. The movable pin ordinarily used in car-seals is entirely dispensed with, 40 and the hasp and keeper may each be and preferably are cast in one piece.

I claim—

1. In a seal-lock, a hasp having an inturned head, a backwardly-extending wing carried 45 by said head, a forwardly-extending wing also carried by said head, a keeper having two outwardly-turned members, a forwardly-extending wing carried by one of said outwardly-turned members, and a rearwardly 50 extending wing carried by the other of said outwardly-turned members, said wings coöperating with the wings carried by said head.

2. In a seal-lock, a hasp having an inturned head, a keeper having a forwardly-opening 55 slot for engaging with said inturned head, a forwardly-projecting member carried by said keeper, said forwardly-projecting member being provided with a seal-wire opening and acting as a stop to limit the movement of said 60 hasp, and a downwardly-projecting member carried by said hasp and provided with a seal-wire opening adapted to register with the said first-mentioned seal-wire opening.

LOUIS A. HOERR.
